to The Hydraulic Development Corporation,
Inc., Mount Gilead, Ohio, a corporation of Dela-
ware

Application September 19, 1940, Serial No. 95,217

Term of patent 7 years

To all whom it may concern:

Be it known that I, Frank E. Sebring, a citizen
of the United States, residing at Mount Gilead, in
the county of Morrow and State of Ohio, have
invented a new, original, and ornamental Design
for a Press, of which the following is a specifica-
tion, reference being had to the accompanying
drawing, forming part thereof, wherein:

Figure 1 is a front elevational view of a press
illustrating my new design;

Figure 2 is a right side elevational view thereof;
Figure 3 is a left side elevational view thereof;
and

Figure 4 is a top plan view thereof.

I claim:

The ornamental design for a press, substan-
tially as shown.

FRANK E. SEBRING.
